LIQUID DISPENSER

Carl A. Gran, Arlington Heights, Ill., assignor to Magi-Pak Corporation, a corporation of Delaware

Filed Feb. 11, 1963, Ser. No. 73,509

Term of patent 14 years

(Cl. D2—3)

FIG. 1

FIG. 3

FIG. 1 is a front perspective view taken from one side of a liquid dispenser showing my new design;

FIG. 2 is a front elevational view thereof, the rear being substantially flat and plain; and

FIG. 3 is an elevational view thereof taken from the side opposite that shown in FIG. 1.

I claim:

The ornamental design for a liquid dispenser, substantially as shown and described.
